DESIGN FOR A JACKET OR SIMILAR GARMENT

Thomas E. Brown, Los Angeles, Calif.

Application January 13, 1936, Serial No. 60,558

Term of patent 3½ years

To all whom it may concern:

I, Thomas E. Brown, a citizen of the United States, residing at Los Angeles, in the county of Los Angeles and State of California, have invented a new, original, and ornamental Design for a Jacket or Similar Garment, of which the following is a specification, reference being had to the accompanying drawing, forming a part thereof.

I claim.

The ornamental design for a jacket or similar garment, substantially as shown and described.

Signed at Los Angeles, California, this 26 day of December, 1935.

THOMAS E. BROWN.
